UNITED STATES PATENT OFFICE.

SAMUEL L. ALLEN, OF CINNAMINSON, NEW JERSEY.

DESIGN FOR A CULTIVATOR-FRAME.

SPECIFICATION forming part of Design No. 19,449, dated December 3, 1889.

Application filed November 7, 1889. Serial No. 329,572. Term of patent 14 years.

To all whom it may concern:

Be it known that I, SAMUEL L. ALLEN, a citizen of the United States, residing at Cinnaminson, in the county of Burlington and State of New Jersey, have invented and produced a new and original Design for Cultivator-Frames, of which the following is a full specification.

Referring to the accompanying drawings, Figure 1 is a plan view of a cultivator-frame showing my design, and Fig. 2 is a side elevation thereof.

The leading feature of my design consists in the configuration produced by a central bar with peculiarly-shaped side bars, one on each side thereof.

A is the central bar, presenting in plan view a perfectly straight appearance. The bar A is provided with a plate or connection D near the forward end thereof.

B b B b are side bars of the shape shown, one on either side of the central bar, the forward ends of which are connected with the

piece D. The shape of the side bars is such that the straight part b is substantially parallel to the central bar and quite near the same, while the curved part B widens out, so that the distance between the rear ends of the two side bars is much greater than that between the straight portions b b, and the rear extremities are parallel with the straight portion b of the front and also with the central bar A. The central bar is connected with the rear ends of the side bars by means of bars C C' on each side, the said bars being arranged in the shape of the letter W.

I claim—

The design for a cultivator-frame herein shown and described.

In witness whereof I have hereunto set my hand.

SAMUEL L. ALLEN.
